UNITED STATES PATENT OFFICE.

ALFRED ERDAHL AND HENRY ERDAHL, OF BLUE EARTH, MINNESOTA.

CUSHION FOR MOUTHPIECES OF MUSICAL INSTRUMENTS.

1,101,420.

Specification of Letters Patent. Patented June 23, 1914.

Application filed June 6, 1913. Serial No. 772,173.

To all whom it may concern:

Be it known that we, ALFRED ERDAHL and HENRY ERDAHL, citizens of the United States, residing at Blue Earth, in the county 5 of Faribault and State of Minnesota, have invented new and useful Improvements in Cushions for Mouthpieces of Musical Instruments, of which the following is a specification.

10 The invention relates to musical instruments and attachments therefor, and has for an object to provide a combined cushion and holder for use on instruments which must be inserted in the mouth in order to be properly 15 played.

The invention embodies, among other features, a device more particularly adapted for use on reed instruments such as clarinets and saxophones and includes a device whereby 20 the instrument will not only be rigidly held in the mouth but whereby the vibration from the reeds will be taken up by the cushion of the device so that the teeth of the player will not receive the jars or vibrations of the 25 reeds. The device also permits of producing a better and softer tone when it is used in connection with clarinets and saxophones, and further prevents the instrument from sliding backward and forward in the mouth 30 when it is being played upon by the player.

In the further disclosure of the invention reference is to be had to the accompanying drawings, constituting a part of this specification, in which similar characters of reference denote corresponding parts in all the 35 views, and in which:

Figure 1 is a perspective view of the mouthpiece of a clarinet, showing our device applied thereto; Fig. 2 is a vertical sectional view showing the manner of mounting our device on the structure disclosed in Fig. 1; and Fig. 3 is a perspective view of the device removed from the mouthpiece disclosed in Fig. 1.

40 Referring more particularly to the views, we disclose a mouthpiece 10 adapted for use in connection with a clarinet or other similar musical instrument, the said mouthpiece having the usual clamp 11 arranged to engage the same and secured to the mouthpiece 45 by means of suitable screws 12 forming a part of the clamp.

Our device consists of a supporting plate

13 provided with a plurality of apertures 14 through which the screws 12 are adapted to 55 pass to rigidly secure the plate 13 to the clamp 11. The upper end of the supporting plate 13 terminates in a lateral extension 15 on which is carried a cushion plate 16 having connected to its free end a suitable 60 cushion 17, preferably formed of rubber or any other suitable material and lying adjacent to the usual opening 18 formed in the mouth end of the mouthpiece 10.

Now it will be apparent that in the use of 65 the device described, when the mouth end of the mouthpiece 10 is inserted in the mouth of the player, the teeth of the player will engage the cushion 17, thus not only aiding in supporting the instrument to which the 70 mouthpiece is attached in playing position, but also permitting of restricting the opening 18 for the purpose of varying the notes or producing a softer tone. By having the teeth of the player in engagement with the 75 cushion, the vibrations of the reeds usually forming parts of saxophones and clarinets will not affect the teeth of the player and the mouthpiece of the instrument can therefore be more firmly gripped in the mouth 80 and prevented from slipping forward or backward therein.

Having thus described our invention, we claim:

1. As a new article of manufacture, a 85 cushion and holder for a musical mouth instrument, the mouthpiece of which has a flat face, consisting of a supporting plate for connection with the mouthpiece of the instrument and a cushion supported on the 90 plate and lying against the flat face of the mouthpiece.

2. In a cushion and holder for musical mouth instruments, a clamp-carrying mouthpiece, a supporting plate rigidly carried on 95 the clamp, a lateral extension formed at one end of the plate, a cushion plate on the extension, and a cushion on the plate and engaging the mouth end of the mouthpiece.

In testimony whereof we affix our signatures in presence of two witnesses.

ALFRED ERDAHL.
HENRY ERDAHL.
